Patented Nov. 11, 1975

237,655

ASPIRATOR-IRRIGATOR

Harvey J. Engelsher, Yonkers, N.Y., assignor to Horizons
Industries, Ltd., New Rochelle, N.Y.

Filed Jan. 2, 1974, Ser. No. 430,238

Term of patent 14 years

Int. Cl. D24—02

U.S. Cl. D83—12 A

FIG. 1.

FIG. 2.

FIG. 4.

FIG. 3.

FIG. 5.

FIG. 1 is an isometric view of an aspirator-irrigator showing my new design;

FIG. 2 is a top plan view thereof;

FIG. 3 is a bottom plan view thereof;

FIG. 4 is a front elevational view thereof, with the back view being the same; and

FIG. 5 is a right side view thereof, with the left side view being the same.

I claim:

The ornamental design for an aspirator-irrigator, as shown and described.
